Des. 100,559

ASHTRAY OR SIMILAR ARTICLE

Filed Dec. 23, 1935

FIG. 1.

FIG. 2.

Wallace E. Harris

INVENTOR.

BY ATTORNEY.

UNITED STATES PATENT OFFICE

100,559

DESIGN FOR AN ASHTRAY OR SIMILAR ARTICLE

Wallace E. Harris, Dallas, Tex., assignor of one-half to Walter F. Gordon, Dallas, Tex.

Application December 23, 1935, Serial No. 60,244

Term of patent 3½ years

To all whom it may concern:

Be it known that I, Wallace E. Harris, a citizen of the United States, residing at Dallas, in the county of Dallas and State of Texas, have invented a new, original, and ornamental Design for an Ashtray or Similar Article, of which the following is a specification, reference being had to the accompanying drawing, forming a part thereof.

I claim:

The ornamental design for an ashtray or similar article.

WALLACE E. HARRIS.
